UNITED STATES PATENT OFFICE.

HENRY W. WALDMIRE, OF PHILADELPHIA, PENNSYLVANIA.

VENTILATOR.

SPECIFICATION forming part of Letters Patent No. 693,193, dated February 11, 1902.

Application filed May 14, 1901. Serial No. 60,207. (No model.)

To all whom it may concern:

Be it known that I, HENRY W. WALDMIRE, a citizen of the United States, residing at Philadelphia, county of Philadelphia, and State of Pennsylvania, have invented a certain new and useful Improvement in Ventilators, of which the following is a specification.

My invention relates to a new and useful improvement in ventilators, and has for its object to provide a ventilator which will be of a cupola form and arranged above the room or apartment to be ventilated and be provided with valves, which valves can be operated entirely from a central rod.

Another object of my invention is to provide hoods or protectors which surround the ventilator in different parts to allow the valves to be open and yet prevent the rain or snow from beating in.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 represents a vertical section through my ventilator, and Fig. 2 is a vertical section taken at right angles to Fig. 1.

In carrying out my invention as here embodied, A represents a base which is adapted to fit over an opening communicating with the apartment to be ventilated. This base A is preferably made square, as is the well-known ventilator. The walls of the base A slant inward, as indicated at B, and form a square portion which is smaller than the base A. Through each of the four walls of this portion are formed openings, which openings are adapted to be closed by pivoted valves C.

The openings which the valves are adapted to close have flanges formed at each side, and the valves C have also flanges upon their sides, and through both these flanges pass the pivots D. A flange E is formed upon the outside of the framework of the ventilator. The lower portion of the valves C are formed so that when the valves are closed over the

openings these flanges E will pass into cavities formed by bending the valve which will prevent the rain from entering the interior of the ventilator when the valves are closed. The upper portions of the valves C have flanges which extend upward upon the interior of the ventilator and when the valves are closed will come in contact with the inside of the walls of the same, and thus prevent the rain or snow from entering above the valves when they are closed.

F is a vertical rod which extends up through the center of the ventilator and is guided in suitable guideways, as represented at G and H. This vertical rod F has secured to it the collar I, which has pivoted to it four rods J, which extend out in four different directions and are pivoted at their other ends to the valves C. Thus when the rod F is pushed upward the valves C will be rocked outward upon the pivots, so as to open the same. The degree that the valves are opened depends upon the distance the rod F is pushed upward. A friction - spring K, secured to the cross-piece G and bearing against the rod, serves to hold the rod F in any desired position.

Above that portion of the ventilator in which the valves C are pivoted the framework projects out horizontally, and from the outer edge of this projecting portion it extends upward in the form of a pyramid, and in two faces of this slanting portion are pivoted large valves L, which are pivoted to the walls of the ventilator at the point l. When these valves L are closed, their lower edges rest within the groove M at the edge of the projecting horizontal portion of the framework for the purpose of preventing rain or snow from beating in. These valves L are opened and closed similar to the valve C by means of rods or links N, one end of which is pivoted to two of the links or rods J and the other ends are pivoted to the valves L. Thus when the rod F is raised or lowered both the valves C and valves L will be opened or closed. The other two sides of the inclined portion corresponding with that portion in which the valves L are located have openings in which glass Q is inserted for the purpose of admitting light. The upper part of the structure has an opening O, which opens up-

ward and is adapted to be normally closed by a cap or valve P, which is secured also to the rod F, and when this rod is pulled to its lowest position the cap or valve P will close the opening; but when the rod F is pushed upward the cap will be raised from off the opening and allow ventilation through this portion of the structure also.

While I have described two of the sides of the pyramidal portion having valves located therein and the other two sides being glazed, it is obvious that valves could be formed in all four sides, or that all four sides could be glazed. The latter construction would probably be preferable, as the lower ventilator C and the central upper ventilator P will allow sufficient ventilation for all practical purposes, and the four sides being glazed will admit a quantity of light while at the same time affording ventilation.

As far as I have described constitutes the ventilator proper and could be used as a ventilator without any further apparatus whatsoever; but in some cases when it would be desirable to open the valves even while it was raining or storming in any other manner I provide shields or hoods which will allow ventilation while at the same time preventing rain or snow from entering through the open valves.

R is a square shield which passes entirely around the outside of the ventilator around that portion in which the valves C are located and is upheld and supported by strips S, which connect the same with the framework of the ventilator. Around the upper portion of the ventilator passes another square shield T, which is upheld and secured to the framework of the ventilator by the strips U. This shield T is open at the top, but suspended within this shield and located directly above the opening O and valve P is a pyramidal-shaped hood V, which is supported by the cross-pieces W, which are secured to the shield T. These hoods or shields do not necessarily have to be used in connection with my particular form of ventilator, but could with a slight variation in the design be used in other forms of ventilators.

The principal advantage of my invention is that by glazing the sides of the pyramidal portion the room to be ventilated is well lighted at all times through the ventilator either when the valves of the ventilator are open or closed.

Another advantage of my invention is that while being comparatively easy and cheap to manufacture it affords the best possible protection against the weather when the valves are closed, and all the valves are easily opened or closed by one operation, and these valves can be opened or closed to any desired degree.

Of course I do not wish to be limited to the exact construction here shown, as slight modifications could be made without departing from the spirit of my invention.

Having thus fully described my invention, what I claim as new and useful is—

1. In a ventilator, the lower portion of which is composed of vertical walls, openings formed through these vertical walls, valves pivoted in said walls and adapted to open or close said openings, the upper portion of said ventilator formed of pyramidal shape, openings formed through two faces of this pyramidal portion, valves pivoted to the framework and adapted to open or close these openings, a central rod passing upward through suitable guideways in the ventilator, connections between all of the valves and this central rod so that when said rod is pushed upward the valves will be opened, openings formed through the other two faces of the pyramidal portion, glass adapted to cover said openings, an opening opening upward through the top of the ventilator, a valve connected to the central rod adapted to open and close said opening, substantially as described and for the purpose specified. 70 75

2. In a ventilator, a rectangular structure the lower portion of which is composed of vertical walls, openings formed through each of the four vertical walls, valves pivoted in these vertical walls and adapted to open or close the opening, a flange extending outward from the vertical walls below the openings, a recess formed in the lower edge of these valves and adapted to embrace said flange when the valves are closed, a central rod extending up through the center of the ventilator, suitable guideways for guiding this rod, a collar secured to the rod, four links, one end of each of which is pivoted to said collar, the other end of each of said links being pivoted to each of the four valves, the upper part of the framework of the ventilator being of pyramidal formation, openings formed through two faces of this pyramidal portion, valves pivoted to the framework and adapted to open or close said openings, grooves formed in the framework of the ventilator into which the ends of the valves are adapted to rest when said valves are closed, two links, one end of each being pivoted to each of the last-named valves, the other end of the links each pivoted to one of the links connecting the collar with the lower valves, openings formed through the remaining faces of the pyramidal portions, glass adapted to be inserted in said openings, an opening formed through the top of the ventilator, a valve secured to the central rod and adapted to open and close said opening, means for holding the central rod in any position it is placed, substantially as described and for the purpose specified. 90 95 100 105 110 115 120 125

3. In a ventilator, a rectangular structure, the lower portion of which is composed of vertical walls, openings formed through each of the four vertical walls, valves pivoted in these vertical walls and adapted to open and close the opening, an opening formed through the upper part of the ventilator adapted to open upward, a central rod, a valve secured upon the upper end of said central rod and

adapted to open or close the upper opening, means whereby the other valves of the ventilator are opened and closed by the movement of the central rod, a shield adapted to surround the lower portion of the ventilator in which the lower valves are placed, a shield adapted to surround the upper portion of the ventilator so as to protect the upper opening horizontally, a hood arranged above the upper opening and adapted to protect said open-

ing vertically, substantially as described and for the purpose specified.

In testimony whereof I have hereunto affixed my signature in the presence of two subscribing witnesses.
